(57) **CLAIM**

The new, original, and ornamental design for a seasoning package, as shown and described.

DESCRIPTION

FIG. 1 is a front elevational view of a seasoning package showing our new design;

FIG. 2 is a right side elevational view thereof, the left side elevational view being a mirror image of the side view shown;

FIG. 3 is a top plan view thereof, the bottom plan view being a mirror image of the plan view shown;

FIG. 4 is a rear elevational view thereof; and,

FIG. 5 is a bottom, front, and right side perspective view thereof.

The lightweight broken line portion of the figure drawings showing a hanger aperture is included to show unclaimed subject matter only and forms no part of the claimed design; the thin dot-dashed line surrounding the central portion of FIG. 4 shows a claimed perforation line.
